DESIGN FOR A HOSIERY JAR OR SIMILAR ARTICLE

Edwin C. Carman, New Orleans, La.

Application April 13, 1944, Serial No. 113,236

Term of patent 14 years

(Cl. D58—25)

To all whom it may concern:

Be it known that I, Edwin C. Carman, a citizen of the United States, residing at New Orleans, in the Parish of Orleans and State of Louisiana, have invented a new, original, and ornamental Design for a Hosiery Jar or Similar Article, of which the following is a specification, reference being had to the accompanying drawing, forming part thereof.

Figure 1 is a front elevational view of a hosiery jar or similar article, showing my new design, and Figure 2 is a top plan view thereof.

I claim:

The ornamental design for a hosiery jar or similar article, as shown.

EDWIN C. CARMAN.
